THREAD OR YARN CLEANER

Arthur E. Truesdell, Pittsfield, Mass.

Application November 17, 1932, Serial No. 643,080

6 Claims. (Cl. 28—64)

My invention more particularly relates to a device commonly known as a slub catcher or "slubber" for removing slubs or other enlargements which frequently occur in textile filaments for making fabric. Such imperfections, if not removed, are likely to break the needles or the yarn when used in knitting machines, and when knitted or woven into cloth cause imperfections therein.

Various types of slubbers are now in use most of which are inefficient as they will remove under 60% of the harmful imperfections in the yarn. Their detecting element is not sensitive enough to cope with the high yarn winding speeds now employed and on closer adjustment they become non-selective and make useless cuts in the yarn. In some devices the yarn wears the detector and soon the proper gauging is lost. In others close adjustment cannot be had without incurring useless breaks in the yarn. A general complaint about the slubbers is that the detection groove cannot be easily and accurately set for the yarn size, thickness gauges being generally used which depend for accuracy on the feel of the setter.

One of the objects of my invention is to provide a device of this character to be both sensitive and selective without incurring useless breaks in the yarn.

Another object is to provide a simple adjustment for the detection groove, both accurate and easily set.

Another object is to provide easy replacement of parts subject to wear as will be evident.

A further object is to provide a selective detection to suit the needs of the particular mill.

My invention will best be understood by reference to the accompanying drawing in which I have illustrated a preferred embodiment thereof and in which—

Fig. 1 is a front elevation of a device embodying my invention;

Fig. 2 is a side elevation thereof;

Fig. 3 is a fragmentary detail illustrating the mounting of the table on the frame;

Fig. 4 is a side view of a modified form of detector shoe enlarged; and

Figs. 5 and 6 illustrate further enlarged modifications of detector shoes.

Like reference characters indicate like parts throughout the drawing.

Referring to the drawing, 10 indicates generally a frame comprising a bracket 11 by which the frame may be secured to a part of the winding machine preferably by a set screw 12, the bracket 45 preferably being wider than the remaining por-

tion of the frame in order to hold the device securely in position. The frame 10 also comprises a standard 13 which extends upwardly and then horizontally as at 14 and then downwardly as at 15. The standard 13 is also provided with extensions 16 and 17. The extension 16 is provided with an elongated slot 18 in which is mounted a shaft 19 preferably provided with an enlarged portion 20 and secured in position by a nut 21. On the shaft are mounted two yarn engaging friction discs 22 and 221 which are held in engagement against the enlarged portion 20 of the shaft by a coil spring 23 which is interposed between the disc 22 and a nut 24 engaging a screw-threaded portion 25 of the shaft 19. It will, of course, be understood that any other form of tension device may be employed to secure proper winding of the yarn on the package.

A guide roller 26 for the yarn is mounted on a shaft secured to the other extension 17. A table 20 27 is secured to the standard 13 by screws 28 one of which is illustrated in Fig. 3 the ends of which are received in tapped openings 29 in the table. The screws 28 pass through slots 30 in the standard 13 thereby permitting vertical adjustment of 25 the table.

A guide plate 31 for the filament is mounted on the table 27 and is preferably secured in position by a clamping plate 32 which is secured to the table 27 by a screw 33, the upper edge of the 30 clamping plate 32 engaging the guide plate 31. The engaging surfaces of the table 27 and the guide plate 31 are inclined with respect to the line of travel of the yarn or thread 34 so that a longitudinal movement of the guide plate 31 with 35 respect to the table 27 raises or lowers the upper surface of the guide plate 31 to a position parallel to its original position. The table is calibrated as at 35 and an adjacently disposed portion of the guide plate is provided with a mark or calibration 36. The calibrations on the table 27 are 40 preferably so made with reference to the inclination of the table and the guide plate, that the longitudinal movement of the guide plate through one calibration represents a vertical 45 movement of 1/1000 of an inch. This construction provides an easy and accurate adjustment of the guide plate. While I have illustrated the calibrations arranged on the faces of the table and the guide plate, it will be understood that 50 the guide plate could be set back from the table and the calibrations placed on the top of the table and the side of the guide plate, or other convenient way.

A combined slub detector and cutter, indicated 55

generally at 37, is provided with a shaft 38 the ends of which are mounted in non-friction bearings 39 mounted in the standard 13 and the downwardly extending portion thereof 15, respectively. The detector 37 comprises an arm 40 provided with an extension 41 on which is mounted an adjustable weight 42 which normally holds the arm 40 in the inclined position illustrated in Fig. 2 against a stop 43 preferably in 10 the form of a pin which is received in an opening 44 in the standard.

The arm 40 is preferably formed of wood or other light material having little inertia thereby improving the sensitiveness of the device. A 15 readily removable metal shoe 45 in the form of an angle piece in the illustrated embodiment of my invention is secured to the lower end of the arm 40 as by a screw 46, the lower portion of the shoe extending across the lower end of the arm 20 40 and paralleling the line of movement of the yarn. It is evident that the shoe may be made in two parts, a blade and a drag which may be separately replaceable. In the embodiment of my invention illustrated in Fig. 2, the lower side 25 of the shoe 45 is provided with a plurality of downwardly extending comparatively narrow projections 47 constituting slab detector elements, the lower edges of which are normally parallel to the upper surface of the guide plate 31, the projection 47 at the forward end preferably being sharpened. It will be noted that the detector elements and the sharpened element are located in advance of the normal from the pivotal point of the detector unit to the line 30 of travel of the filament. When the detector 37 is held in the position illustrated in Fig. 2 the lower edges of the elements 47 and 471 of the shoe 45 are equally distant from the top of the guide plate 31. The guide plate 31 is so adjusted with reference to the detector shoe, that the filament of yarn or thread of normal thickness will just pass between the guide plate and the shoe without moving the latter. When an enlargement, however, such as a slab 48 occurs 35 in the yarn or other fibrous filament, the arm 40 is tilted to the right as viewed in Fig. 2 about its pivot and the knife edge 471 or other detector bites into the thread and severs it where the slab or other enlargement occurs. By the provision 40 of a multiplicity of detection elements of the proper character, the efficiency of the detector unit is increased.

The operation of the device is as follows.

The yarn or other fibrous filament 34 is wound 45 from a suitable bobbin, tube or reel and passes between the friction discs 22 and 221 over the guide plate 31 and the guide roller 26 to a package, not illustrated.

The table 27 and guide plate 31 which is mounted thereon have previously been set by means of screws 28 to best accommodate the various sizes of yarn to be wound. This means that if the yarns to be used require an average spacing 50 below the shoe 45 of .015 of an inch, the table 27 and guide plate 31 will be set to make the spacing .015 of an inch, when the guide plate 31 is in midposition on the table. This setting can then be easily modified on a change of yarn size by 55 loosening clamp 32 and sliding the guide plate 31 forward or backward to give the required new spacing. In the position shown the spacing is .017 of an inch.

Any substantial enlargement in the yarn such 60 as a slab will encounter one of the detector ele-

5 element to swing to the right in the direction of yarn travel enabling element 471 to sever the yarn. The slab is then removed by the operator in the usual way, a knot tied in the yarn and winding renewed.

By removing the stop 43, the arm 40 may be moved upwardly so as to expose the lower side of the shoe and permit ready cleaning thereof.

In Fig. 4 I have illustrated a modified form of 10 shoe which is particularly intended for detecting and removing "coarse yarn." In this case the shoe is provided with a cutting edge 471 as in the case of Fig. 2, but is also provided at the rear thereof with a comparatively large projection 442 having a correspondingly large lower 15 area to engage the enlarged yarn. The shoe illustrated in Fig. 4 may be made even more effective by roughening the lower surface of the projection 442.

Fig. 6 illustrates a design of shoe provided with 20 three detector elements 444 particularly useful for detecting slubs as distinguished from coarse yarn, and Fig. 5 illustrates a device intermediate between the devices of Fig. 4 and that of Fig. 6, the same being provided with two 25 detector elements 443.

The above designs of shoes provide differing means from which the user can select the one most suitable for his needs.

While I have described my invention in its 30 preferred embodiments, it will be understood that the words which I have used are words of description rather than of limitation and that changes within the purview of the appended 35 claims may be made without departing from the true scope and spirit of my invention in its broader aspects.

What I claim is:

1. In a device of the character described, a 40 frame, a detector unit swingingly mounted thereon, a table mounted on said frame, a guide plate over which a filament of fibrous material is movable mounted on said table, the engaging surfaces of said table and said plate being oppositely inclined with respect to the line of travel 45 of said filament, whereby the longitudinal movement of said plate varies the distance thereof from said unit, and means for adjustably holding said plate to said table.

2. In a device of the character described, a 50 frame, a detector unit swingingly mounted thereon, a table mounted on said frame, a guide plate over which a filament of fibrous material is movable mounted on said table, the engaging surfaces of said table and said plate being oppositely inclined with respect to the line of travel of said 55 filament, whereby the longitudinal movement of said plate varies the distance thereof from said unit, said table and said plate being provided with adjacently disposed calibrated portions, and means for adjustably holding said plate and said table together.

3. In a device of the character described, a 60 frame, a detector unit swingingly mounted thereon, a table mounted on said frame, a guide plate over which a filament of fibrous material is movable mounted on said table, the engaging surfaces of said table and said plate being oppositely inclined with respect to the top surface of 65 said plate, whereby the longitudinal movement of said plate varies the distance thereof from said unit, means for adjustably holding said table and said plate together, and means whereby said table and said plate may be moved bodily towards and away from said unit.

4. In a device of the character described, a
swingingly mounted detector unit, a table, a
guide device over which a filament of fibrous
material is movable mounted on said table, the
engaging surfaces of said table and said device
being oppositely inclined with respect to the top
surface of said device whereby the longitudinal
movement of said device varies the distance there-
of from said unit and means for adjustably hold-
ing said table and said device together.

5. In a device of the character described, a
swingingly mounted detector unit, a table, a guide
device over which a filament of fibrous material
is movable mounted on said table, the engaging
surfaces of said table and said device being op-
positely inclined with respect to the top surface
of said device whereby the longitudinal move-
ment of said device varies the distance thereof

from said unit, means for adjustably holding said
table and said device together and means where-
by said table and said device may be moved bod-
ily towards and away from said detector unit.

6. In a device of the character described, a
frame, a detector unit mounted thereon, a table
mounted on said frame, a guide plate mounted
on said table, means for guiding a filament of
fibrous material over the top of said plate, said
filament being movable vertically with said plate,
the engaging surfaces of said table and said
plate being oppositely inclined with respect to
the line of travel of said filament whereby the
longitudinal movement of said plate varies the
distance thereof from said detector unit, and
means for adjustably securing said plate to said
table.

ARTHUR E. TRUESDELL.

CERTIFICATE OF CORRECTION.

Patent No. 2,002,843.

May 28, 1935.

ARTHUR E. TRUESDELL.

It is hereby certified that error appears in the printed specification of the above numbered patent requiring correction as follows: Page 2, first column, line 72, strike out the syllable and words "ments 47 or 471 which will cause the detector" and insert the same after "line 75, of same page and column; and that the said Letters Patent should be read with this correction therein that the same may conform to the record of the case in the Patent Office.

Signed and sealed this 9th day of July, A. D. 1935.

Bryan M. Battey
